UNITED STATES PATENT OFFICE.

FREDERICK BOOTH, OF LAPORTE, INDIANA.

SPIRAL TOOL-DRIVER.

1,330,053.

Specification of Letters Patent. Patented Feb. 10, 1920.

Application filed June 15, 1918. Serial No. 240,189.

To all whom it may concern:

Be it known that I, FREDERICK BOOTH, a citizen of the United States, residing at Laporte, county of Laporte, and State of Indiana, have invented certain new and useful Improvements in Spiral Tool-Drivers, of which the following is a specification.

This invention relates to tool drivers of the class in which a chuck carried on the end 10 of a spindle and adapted to receive tool bits is rotated by the reciprocation of the handle in which the spindle is carried, and more particularly to the kind shown in my prior United States Patent No. 1,183,426 of May 15 16, 1916, in which a suitable gear wheel is secured to the spindle and is rotated through engagement with a stationary rack within the handle portion of the tool. In devices 20 as disclosed in my prior patent the spindle may be rotated in but a single direction, but in my present invention I provide a novel ratchet means by which the direction of rotation may be reversed or the spindle may be held against rotation in either 25 direction.

A further object of the invention is to provide means for changing the direction of rotation of the spindle irrespective of the relative position of the spindle in the handle.

30 A further object of the invention is to provide a tool of this kind which may be locked at will in extended or retracted position and be used as a ratchet or rigid tool, whereby the use of the tool under different 35 conditions may be more convenient.

Heretofore in tools of this kind where the direction of rotation of the spindle may be varied it has ordinarily been necessary to provide the spindle with oppositely inclined 40 threads or grooves and to provide rotatable collars or sleeves in the tool handle relatively stationary thereto and having means for engaging the grooves to impart motion to the spindle. Such tools are provided with 45 a suitable pawl or pawls for locking one of the collars to thereby effect rotation of the spindle in the desired direction. Experience in connection with the use of devices as shown in my prior U. S. patent above referred to has shown that the efficiency of the 50 tool is increased where a stationary rack is secured in the tool handle and the gears for rotating the spindle are mounted on the spindle and reciprocate with the spindle 55 relatively to the handle.

According to my present invention, therefore, I provide a suitable tubular handle portion of desired length in which is fastened a rack having oppositely inclined teeth therein. Guided in a bearing at one end of 60 the tubular handle and having its inner end provided with a suitable bearing adapted to engage the inner walls of the tube is a spindle, the outer projecting portion of which is provided with a chuck for receiving 65 suitable tool bits, as screw drivers and drills. Near the inner end of the spindle and rotatably mounted thereon are two gear wheels adapted to engage the oppositely inclined teeth of the rack whereby they are 70 rotated upon the reciprocation of the rack. A suitable clutch member is provided whereby the motion of either one of the gears may be imparted to the spindle or whereby both 75 may be held immovable relatively to the spindle at the same time to prevent the spindle from being rotated within the handle. Suitable means extending substantially the 80 length of the tubular handle is provided for operating the clutch mechanism irrespective of the position of the spindle relatively to the handle.

In ratchet tools heretofore constructed there has been no means provided for preventing the spindle from moving to projected position during the operation thereof, or for locking the tool in projected position and while so locked permitting of its use as a ratchet tool. By the present construction these disadvantages are overcome 90 and a lock mechanism is provided whereby the tool spindle may be locked in either extreme position and still be used as a ratchet tool.

Referring now to the accompanying drawings:—

Figure 1 shows an elevation of my tool.

Fig. 2 shows a longitudinal section of the tool.

Fig. 3 shows a transverse section on line 3—3 of Fig. 2.

Fig. 4 shows a transverse section on line 4—4 of Fig. 2.

Fig. 5 shows a transverse section on line 5—5 of Fig. 2.

Fig. 6 shows a transverse section on line 6—6 of Fig. 2.

Fig. 7 shows a transverse section on line 7—7 of Fig. 2.

Fig. 8 shows a transverse section corre-

sponding to Fig. 7 but showing the shifting mechanism moved to inoperative position.

Fig. 9 shows a transverse section on line 5 9—9 of Fig. 2.

Fig. 10 shows a transverse section on line 10—10 of Fig. 2.

Fig. 11 shows a transverse section on line 11—11 of Fig. 2.

Fig. 12 shows a transverse section on line 10 12—12 of Fig. 2.

Fig. 13 shows an inverted perspective view of the slide for effecting the movement of the clutch mechanism.

Fig. 14 shows in detail one of the gear wheels and the ratchet by means of which motion is imparted to the spindle.

Fig. 15 shows a perspective view of the tubular handle.

Fig. 16 represents in perspective a portion of a bar extending substantially the length of the tubular handle for effecting the movement of the shifting mechanism.

Fig. 17 represents a transverse section 25 therethrough.

Fig. 18 represents a portion of the casing.

Fig. 19 shows on an enlarged scale part of the shifting mechanism.

Fig. 20 shows in detail the slide for moving the locking mechanism.

Fig. 21 shows a spring employed in the locking mechanism while Fig. 22 represents the locking plate.

Fig. 23 shows a detail view of an oil pad.

Fig. 24 represents an end view of a washer in the casing.

Referring now more particularly to the accompanying drawings I have shown a handle 1, which may be of any desired construction, but preferably of wood, and having secured therein a metallic casing comprising a tubular portion 2 adapted to carry the tool actuating mechanism. Adapted to work in the handle and casing is a spindle 4 carrying a tool holding chuck 5 of any suitable construction on its outer end. The spindle is of substantially the same diameter throughout the greater portion of its length and is supported in the outer end of the tube 2 by a cap 6 in which is a ball bearing 7. Separated from the ball bearing 7 by a plate 8 is a felt oil and dust collecting pad 9. The cap 6 is preferably provided with a washer 10 having an opening 10' having a resilient closing flap 11 preferably formed integrally therewith, whereby the snout of an oil can may project therethrough. Secured within the casing 2 is a rack 12 having oppositely inclined teeth or spiral-threads.

60 The inner end of the spindle is guided by two bearings 14 and 15, see Fig. 2. The bearing 14 is on the extreme inner end of the spindle, while the bearing 15 is spaced somewhat farther along toward the middle thereof. Each of these bearings comprise

a ball race 16 secured to the spindle by a suitable pin. Surrounding the ball race 16 is a ball spacer 17 in which are a plurality of balls 18. I preferably employ four comparatively large balls, it being well known that the larger balls roll over more easily than the small ones. These balls are of sufficient size to engage the ball race and the inside walls of the tube 2 whereby any lateral motion of the spindle is entirely prevented. The ball spacers 17 do not extend entirely around the ball race but project tangentially to engage the sides of the rack, see Figs. 3, 9 and 10, whereby they are prevented from rotation. Projecting from the ball spacers 17 are lugs 19, preferably two lugs being provided on each spacer (see Figs. 2 and 10). Carried by the ball spacer 17 is a felt oil pad 13 for keeping the balls and the interior of the tube oiled and for collecting particles of grit that may work into the tube. These pads are held in place by plates 13'.

The spindle rotating mechanism is disposed between the two sets of balls and comprises two oppositely threaded or toothed, spaced apart spiral or helical gear wheels A and B mounted to freely rotate on the spindle 4. Each gear is provided with one or more pawls or ratchet teeth A' and B' respectively, (see Fig. 14). Mounted on the spindle 4 adjacent the gears A and B are ratchet wheels A² and B² respectively, having oppositely inclined ratchet teeth thereon. The ratchet wheels A² and B² are keyed 95 to the spindle by means of a pin 20 projecting into slots 21 in the ratchet wheels. In this manner the ratchet wheels A² and B² may be moved into and out of contact with their respective driving pawls A' and B', and thereby be made to transmit rotary motion of the gears A or B to the spindle. The ratchet wheels are normally held out of contact with the pawls A' and B' by coil springs 22 pushing against the ends of the 100 gear wheels A and B and the collar 23 on ratchet wheels A² and B². It may thus be seen that by bringing the pawl A' into engagement with ratchet wheel A² and rotating gear A by reciprocating the handle and the rack relatively thereto the spindle 4 may be rotated in one direction when the handle is pushed toward retracted position, the pawl and ratchet teeth preventing the rotation when the handle is being moved to extended position. During this time the gear B will rotate freely. By bringing pawl B' 115 into engagement with ratchet B² the rotation of the spindle is reversed. If A' and B' are engaged simultaneously with their respective ratchets A² and B² the spindle will be prevented from rotating in either direction by the application of pressure to the handle, as in the well known types of ratchet screw drivers now in commercial use. 120 130

For moving the ratchets as desired, I have provided a shifting device 25 carried by the spindle but having a limited sliding movement relatively thereto. This shifting mechanism comprises two similar sections 26 and 26' secured together (see Fig. 2). Each section, as shown in Fig. 19, consists of a single piece of thin resilient metal having a base portion 27 corrugated at 28 to make that portion of the base elastic. It is against the spring portion 28 that ratchets A and B move during the movement of the handle in one direction. On one end of the base is a disk shaped end 29 at right angles to the base and having an opening therethrough through which the spindle 4 is passed. It is provided with inturned edges 30 adapted to hold a felt or other suitable oil pad and dust collector 31 (see Fig. 23), which pad 20 coming in contact with the rack keeps that member and both spirals well oiled. The opposite face of the disk portion 29 is adapted to bear against the collars 23 of ratchet wheels A² or B². The opposite end of the 25 base portion 27 of each section is bent angularly to form a spring portion 31 which supports the vertical part 32. The top of the part 32 is provided with a sharp projecting lug 34. The vertical parts 32 of each section adjacent to each other are secured together in any suitable way (see Fig. 2). The shoulders 35 on the vertical ends 34 are adapted to be normally held in one of the annular grooves a, b, or c in the spindle 35 4 between the two gear wheels A and B, by the upward pressure of the spring 31 of each section. Disposed between the two ends, 29 and 34 is a curved arm 36 having projections 37 thereon and bearing against the walls of 40 the tubular casing 2, by which the shifting mechanism is held in proper position in the tube. A longitudinal projection 38 is provided on the curved arm 36 and has a lug 33 thereon for engagement with the gear A or B to regulate the sliding movement of 45 the shifting mechanism. It will be seen that by pressing down on lug 34 shoulder 35 may be disengaged from the grooves a, b and c on the spindle 40 as indicated in Fig. 50 8 and the shifting mechanism may be moved in the desired direction whereby the ratchet wheels A² and B² may be moved into and out of engagement with the driving pawls A' and B'. For instance, if shoulder 35 is in engagement with groove a, B' and B² will be in engagement and A' and A² will be disengaged. If the shifting mechanism is locked at b, A' and A² will be in engagement and B' and B² will be disengaged. If 55 60 the shifting mechanism is set at the middle groove c, both ratchets A² and B² will be engaged and the spindle held from rotation.

For moving the shifting mechanism irrespective of its position relatively to the handle I have provided a slot 38 extending

throughout the major portion of the length of the tube 2 and having depressions 39 at each end. There is also provided a second slot 40 of comparatively short length. A ribbed strip 41 is provided in slot 38 and is 70 slidably supported therein by springs 42 secured to either end thereof and having their free ends resting in the depressions 39. This strip 41 is provided throughout its length with serrations or teeth. Secured to 75 the strip 41 is a plate 44, as shown in Fig. 13, which plate is provided with lugs 45 and a projection 46 on the upper surface thereof. The projection 46 is preferably roughened as indicated in order that it may 80 better be moved by the thumb or finger of the operator. For protecting the exposed parts of the strip 41 and plate 44, I have provided a second plate 47 as shown in Fig. 18, which is adapted to be secured to the 85 tube 2 in any suitable manner, and which has a longitudinally extending portion 48 covering the exposed portion of the slot, and a laterally projecting part 49 covering the shorter slot 40. A portion of the plate 47 90 above the plate 44 is pressed outwardly and is provided with a slot 50 through which projection 46 extends. On the interior of the raised portion are secured strips 51 having recesses a', b', c' therein. These recesses 95 are so formed that the lugs 45 on the plate 44 may be normally projected therein, in which position they are normally held by the springs 42 on the strip 41. By pressing down on the projection 46 the lugs 45 are 100 disengaged from any one of the recesses a', b', or c' in which they may have been last projected, and the serrations or teeth on the strip 41 are brought into engagement with the sharp lug 34 on the shifting mechanism. This downward pressure transmitted through lug 34 disengages the shoulder 35 from one of the annular recesses a, b, or c, depending on the position of the shifting device. By sliding the projection 46 longitudinally the motion is thus transmitted through the strip 41 to the shifting device. As the teeth or serrations extend the entire length of the strip 41, it will be seen that the shifting may be accomplished irrespective 105 of the relative position of the handle and the spindle. At the same time the relation between the shifting device and the sliding plate 44 is always maintained, the positions a, b, c of the shifting device corresponding 110 to positions a', b', c' of the sliding plate, so that, for instance, when the lugs 45 on the sliding plates are in the recesses a' the shoulder 35 of the shifting device will engage the recess a on the spindle.

As it is often desirable to use a screw driver as a ratchet tool without any possibility of having a relative longitudinal movement between the spindle and the handle, either when the spindle is in projected 130

or retracted position, I have provided means independent of the ratchet mechanism for securely locking the spindle in either of these positions. These means preferably comprise a plate 52 having inwardly turned lugs 53 (see Fig. 22) supported above the slot 40 in the tube 2 by means of a flat spring 54 (see Fig. 21). As shown in Fig. 10 this spring normally keeps the plate 52 from projecting the lugs 53 through the slot 40. Mounted in the plate 47 is a slide 55 (see Fig. 20) having a projecting portion 56 extending through a slot 57 in the plate 47. The slide 55 has a sloping portion 58 adapted to engage the plate 52 to force the lugs 53 through the slot 40 when the slide is moved to locking position. When the lugs 53 are projected through the slot 40 into the interior of the tube 2 and the spindle is in retracted position they will engage the lugs 19 on the ball spacer 17 of the ball bearing 15. If, however, the spindle is in extended position the lugs 53 will engage the lugs 19 on the ball bearing 14. In either instance, however, it will be seen that the longitudinal movement of the spindle will be prevented without interfering with the ratchet mechanism. When it is desired to release the locking mechanism, the slide 55 is moved in the opposite direction and the plate 52 returned to its normal position by the action of the spring 54. The slide is preferably provided with a rounded end portion 60 forming a bead which normally engages a recess 61 or 61' to hold the slide against movement.

From the foregoing it will be seen that I have provided a tool which is practically dust proof and which is provided with oil and dust collecting pads whereby any particles of grit may be removed from the actuating mechanism and the wear of the tool is thereby prevented to a greater degree than has heretofore been possible in tools of this kind, in which the spindle is provided with spiral grooves which carry dirt into the ratchet mechanism.

While I have described the preferred embodiment of my invention it will be obvious that changes may be made therein within the scope of the appended claims without departing from the spirit of my invention.

I claim as my invention:

1. In a tool, the combination of a spindle casing, a rotary spindle mounted to move into and out of said casing, and means for locking said spindle in either its inner or outer position without interfering with the rotation thereof.

2. In a tool, the combination of a spindle casing, a spindle mounted to move into and out of said casing, a plate having lugs normally out of engagement with the spindle, and a slide for moving said lugs into operative engagement with the spindle to lock same in either its inner or outer position.

3. In a tool, the combination of a spindle casing, a spindle mounted to move into and out of said casing, means for rotating said spindle, and means for locking said spindle in either its inner or outer position, said locking means permitting rotation of the spindle. 70

4. In a tool, the combination of a spindle casing, a spindle mounted to move into and out of said casing, ratchet mechanism controlling the rotation of said spindle in either direction, and independent locking means permitting rotation of the ratchet mechanism for holding the spindle in either its inner or outer position. 75

5. In a tool, the combination of a spindle casing, a spindle mounted to move into and out of said casing, bearings on said spindle and movable therewith, lugs on said bearings, locking means normally out of engagement with said lugs, and means for moving said locking means into engagement with the lugs whereby the spindle may be locked in either its inner or outer position. 80

6. A tool, comprising a spindle casing, a rack having oppositely inclined teeth disposed longitudinally in the casing, a spindle mounted to move into and out of said casing, oppositely rotatable gears on said spindle adapted to engage said rack, and means for imparting the rotation of the gears to the spindle. 90

7. A tool, comprising a hollow spindle casing, a rack bar having oppositely inclined teeth disposed longitudinally in the spindle 100 casing, a spindle mounted to move into and out of said casing, gear wheels on said spindle having oppositely arranged teeth for engagement with said rack bar, means for imparting the rotation of either one of said 105 gears to the spindle, shifting means co-operating with the spindle rotating means for rotating the spindle in the desired direction, and means for moving the shifting means irrespective of the position of the spindle in 110 the casing.

8. A tool, comprising a spindle casing, a rack having oppositely inclined teeth disposed longitudinally in the casing, a spindle mounted to move into and out of said casing, 115 gears having oppositely inclined teeth on said spindle adapted to engage said rack whereby they are rotated in opposite directions, and means for imparting the rotation of either one of the gears to the spindle for 120 rotating the spindle.

9. A tool, comprising a spindle casing, a rack having oppositely inclined teeth disposed longitudinally in the casing, a spindle mounted to move into and out of said casing, 125 gears having oppositely inclined teeth on said spindle adapted to engage said rack whereby they are rotated in opposite directions, and means for imparting the rotation of either one of the gears to the spindle for 130

- rotating the spindle or for simultaneously bringing both gears into operative engagement with the spindle to hold the spindle from rotation.
- 5 10. A tool, comprising a spindle casing, a rack having oppositely inclined teeth in the casing, a spindle mounted to move into and out of said casing, gears having oppositely inclined teeth on said spindle adapted to engage said rack whereby they are rotated in opposite directions, ratchet means for imparting the rotation of the gears in a single direction to the spindle, and means for moving the gears into and out of driving connection with the spindle.
- 10 11. A tool, comprising a spindle casing, a rack having oppositely inclined teeth in the casing, a spindle mounted to move into and out of said casing, gears having oppositely inclined teeth on said spindle adapted to engage said rack whereby the gears are rotated in opposite directions, means for imparting the rotation of either one of the gears to the spindle, and means for moving the gears into and out of driving relation with the spindle irrespective of the position of the spindle in the casing.
- 15 12. A tool, comprising a spindle casing, a rack having oppositely inclined teeth in the casing, a spindle mounted to move into and out of said casing, gears having oppositely inclined teeth on said spindle adapted to engage said rack whereby the gears are rotated in opposite directions, ratchet means for imparting the rotation of either one of the gears to the spindle, and means for moving said ratchet means into and out of driving relation with the spindle irrespective of the position of the spindle in the casing.
- 20 13. A tool, comprising a spindle casing, a rack having oppositely inclined teeth in the casing, a spindle mounted to move into and out of said casing, gears having oppositely inclined teeth on said spindle adapted to engage said rack whereby they are rotated in opposite directions, ratchets for imparting the rotation of either of the gears to the spindle, means for moving the ratchets into and out of driving relation with the spindle, and an oil pad carried by said moving means.
- 25 14. A tool, comprising a spindle casing, a rack having oppositely inclined teeth in said casing, a spindle mounted to move into and out of said casing, two gear wheels having oppositely inclined teeth mounted on said spindle and adapted to engage said rack whereby they are rotated in opposite directions, ratchets for imparting the rotation of the gears in one direction to the spindle, shifting means for moving said ratchets into and out of engagement with the gears and means for moving said shifting means irrespective of its position in the spindle casing.
- 30 15. A tool, comprising a spindle casing, a rack having oppositely inclined teeth in the casing, a spindle mounted to move into and out of said casing, two gear wheels on said spindle having oppositely inclined teeth adapted to engage said rack whereby the gears are rotated in opposite directions, ratchets for imparting the rotation of the gears in one direction to the spindle, shifting means carried by the spindle for moving said ratchets into and out of operative engagement with the gears, and means for locking the shifting means in any one of three desired positions whereby the spindle may be rotated in the desired direction or may be held against rotation.
- 35 16. A tool comprising a spindle casing, a rack having oppositely inclined teeth disposed longitudinally in the casing, a spindle mounted to move into and out of said casing, two gear wheels on said spindle having oppositely inclined teeth adapted to engage said rack whereby the gears are rotated in opposite directions, ratchets for imparting the rotation of the gears in one direction to the spindle, shifting means carried by the spindle for moving said ratchets into and out of operative engagement with the gears, and means for locking the shifting means in any one of three desired positions whereby the spindle may be rotated in the desired direction or may be held against rotation.
- 40 17. A tool, comprising a spindle casing, a rack having oppositely inclined teeth disposed longitudinally in the casing, a spindle mounted to move into and out of said casing, two gear wheels on said spindle having oppositely inclined teeth adapted to engage said rack whereby the gears are rotated in opposite directions, ratchets for imparting the rotation of the gears in one direction to the spindle, shifting means carried by the spindle for moving said ratchets into and out of operative engagement with the gears, means for locking the shifting means in any one of three desired positions whereby the spindle may be rotated in the desired direction or may be held against rotation, and means for disengaging said shifting means from the locking means and moving it to either of the other desired positions irrespective of the position of the spindle in the casing.
- 45 18. A tool, comprising a spindle casing, a rack having oppositely inclined teeth disposed longitudinally in the casing, a spindle mounted to move into and out of said casing, two gear wheels having oppositely inclined teeth on said spindle adapted to engage said rack whereby the gears are rotated in opposite directions, ratchets for imparting the rotation of the gears in a single direction to the spindle, shifting mechanism carried by the spindle for moving said ratchets into and out of engagement with said gear wheels whereby the spindle may be rotated in the desired direc-

- tion, means for moving the shifting mechanism irrespective of the position of the spindle in the casing, means for limiting the movement of the shifting mechanism, and 5 means for holding the shifting mechanism in the desired position.
19. A tool, comprising a spindle casing, a rack having oppositely inclined teeth in the casing, a spindle mounted to move into and 10 out of said casing, two gear wheels having oppositely inclined teeth on said spindle and adapted to engage said rack whereby they are rotated in opposite directions, a ratchet for engagement with each of said gears for 15 imparting the rotation of the gears in one direction to the spindle, and shifting mechanism for moving said ratchets into and out of engagement with the gears irrespective of the position of the spindle in the casing.
20. A tool, comprising a spindle casing, a rack having oppositely inclined teeth disposed longitudinally in the casing, a spindle 20 mounted to move into and out of said casing, two gear wheels having oppositely inclined 25 teeth carried on said spindle and adapted to engage said rack whereby they are rotated in opposite directions, a ratchet for engagement with each of said gears secured to the spindle whereby the rotation of the 30 gears in one direction may be imparted to the spindle, shifting mechanism for moving said ratchets into and out of engagement with the gears, a lug on said shifting mechanism, a strip extending substantially the 35 length of the casing and having teeth therein for engagement with the lug of the shifting mechanism, means for normally holding said strip out of engagement with the lug, and means for moving said strip into engagement with the lug for moving the shifting 40 mechanism.
21. A tool, comprising a spindle casing, a rack having oppositely inclined teeth disposed longitudinally in the casing, a spindle 45 mounted to move into and out of said casing, two gear wheels having oppositely inclined teeth carried on said spindle and adapted to engage said rack whereby they are rotated in opposite directions, a ratchet 50 for engagement with each of said gears secured to the spindle whereby the rotation of the gears in one direction may be imparted to the spindle, shifting mechanism for moving said ratchets into and out of engagement 55 with the gears, means for holding said shifting mechanism in any one of three desired positions, a strip slidably mounted in said casing and extending substantially the entire length thereof, means on said strip 60 for engagement with said shifting mechanism for effecting its movement to any of the three desired positions means for holding said strip normally out of engagement with the shifting mechanism, and means for holding said strip in any one of three de-

sired positions corresponding to the position of the shifting mechanism.

22. A tool, comprising a spindle casing, a rack having oppositely inclined teeth disposed longitudinally in the casing, a spindle mounted to move into and out of said casing, gears on said spindle adapted to engage said rack, each of said gears having oppositely disposed teeth thereon whereby they are rotated in opposite directions, 70 ratchets for engagement with each of said gears for imparting the rotation of the gears in one direction to the spindle, shifting mechanism for moving said ratchets into and out of engagement with the gears, 75 means for holding said shifting mechanism in any one of three desired positions, a slide for effecting the movement of said shifting means, and means for holding the slide in any one of three desired positions, 80 said positions corresponding to the positions of the shifting mechanism.

23. A tool, comprising a spindle casing, a rack having oppositely inclined teeth in the casing, a spindle mounted to move into and 90 out of said casing, gearing on the spindle for engaging the rack and imparting motion to the spindle, and a ball bearing on the end of said spindle, said ball bearing comprising a ball race secured to the shaft and rotatable 95 therewith, a ball spacer moving with said ball race and having means for preventing its rotation, balls carried in said ball spacer, and a felt pad surrounding the ball spacer.

24. A tool, comprising a spindle casing, a 100 rack in said casing, a spindle mounted to move into and out of said casing, a ball bearing disposed on the inner end of said spindle adapted to engage the walls of the casing, a similar ball bearing on the spindle having 105 a spaced relation to the first bearing, and gearing disposed between the bearings for engagement with the rack and imparting rotation to the spindle.

25. A tool, comprising a spindle casing, a 110 rack in said casing, a spindle mounted to move into and out of said casing, a ball bearing disposed on the inner end of said spindle adapted to engage the walls of the casing, a similar ball bearing on the spindle 115 having a spaced relation to the first bearing, gearing disposed between the bearings for engagement with the rack and imparting rotation to the spindle, locking means in said casing adapted to engage said 120 ball bearings, and means for projecting the locking mechanism into and out of the path of the bearings.

In testimony whereof, I have hereunto subscribed my name.

FREDERICK BOOTH.

Signed as witnesses:

CHARLES W. HARRISON,
CHESTER BUNTON.
